Primary Examiner — Ania Aman(74) *Attorney, Agent, or Firm* — Miles & Stockbridge P.C.; David R. Schaffer(57) **CLAIM**

The ornamental design for a hydro-kinetic reactor tank, as shown and described.

DESCRIPTION

FIG. 1 is a front perspective view of a hydro-kinetic reactor tank showing my new design;

FIG. 2 is a rear elevational view thereof;

FIG. 3 is a top plan view thereof;

FIG. 4 is a left side elevational view thereof and an unshown right side is a mirror image of the left side view;

FIG. 5 is a front elevational view thereof; and,

FIG. 6 is a bottom plan view thereof.

The elements shown in broken line are for illustrative purposes only and form no part of the claimed design.
